DESIGN FOR A BOTTLE

Richard J. Puhl, Chicago, Ill., assignor to The John Puhl Products Company, Chicago, Ill., a corporation of Illinois

Application July 7, 1939, Serial No. 85,869

Term of patent 14 years

To all whom it may concern:

Be it known that I, Richard J. Puhl, a citizen of the United States, residing at Chicago, in the county of Cook and State of Illinois, have invented a new, original, and ornamental Design for a Bottle, of which the following is a specification, reference being had to the accompanying drawing, forming part thereof.

Fig. 1 is a front elevation of a bottle showing
my new design.

Fig. 2 is a side elevation of a bottle showing my new design.

Fig. 3 is a plan view of a bottle showing my new design.

I claim:
The ornamental design for a bottle, as shown.

RICHARD J. PUHL.
